FOUNTAIN BRUSH

Filed Oct. 24, 1929

Thomas E. Modd

INVENTOR

BY *Frank J. Baldwin*

ATTORNEY

UNITED STATES PATENT OFFICE

THOMAS E. MODD, OF DETROIT, MICHIGAN

FOUNTAIN BRUSH

Application filed October 24, 1929. Serial No. 402,284.

This invention relates to improvements in fountain brushes, and aims to provide such a brush consisting of a reservoir and a removable brush which fits thereon. The reservoir is intended to have a tube or other container temporarily mounted thereon so that the contents of the latter may be transferred to the former; and the brush shank which is removable from the reservoir has a substantially central opening therethrough, bristles extend outwardly from the brush shank around the opening, and a sliding shutter is provided for closing the opening so that the contents of the reservoir may be prevented from passing through the brush shank to the bristles. Moreover the brush shank may, if preferred, be attached directly to the end of a container such as a shaving soap tube.

With these and other objects and advantages in view which will become apparent as the specification proceeds, the invention is hereinafter more fully described with the aid of the accompanying drawings, in which:

Figure 1 illustrates a side view of the invention.

Figure 2 is a sectional view thereof, and

Figures 3 and 4 are sections on the lines 3—3 and 4—4 of Figures 1 and 2 respectively.

Figure 5 shows a method of filling the reservoir.

Figure 6 depicts the removable brush mounted directly on the end of a tube.

Figure 7 is a section on the line 7—7 of Figure 6, but with the bristles removed.

Figure 8 is a section on the line 8—8 of Figure 7.

Referring now to Figures 1 to 4 of the drawings, 1 designates a reservoir having a tubular neck 2 thereon which is preferably threaded both externally and internally at 3 and 4. Extending longitudinally of the reservoir and substantially centrally thereof is a threaded spindle 5 having a disc 6 in threaded engagement thereon the margins of which bear against the bore of the reservoir. In the event of the latter being circular any desired means may be employed

for preventing rotation of the disc as the spindle is turned. One end of the spindle 5 extends through an aperture 7 in the base 8 of the reservoir and has a plate 9 secured thereon so that rotation of the latter causes the spindle to turn. The opposite end of the spindle is mounted in a spider 10 formed in the inner end of the neck 2, so that the said spindle is held against axial movement. The space A between the disc 6 and the neck 2 is intended to be filled with soap or other material to be applied to the bristles of a brush, and as the disc is advanced towards the neck by rotation of the plate 9 the contents of the space A is forced out through the neck.

12 denotes an annular brush shank having an internally threaded portion 13 extending partway therethrough. This portion 13 engages the external thread 3 on the neck 2. 70 14 indicates a continuation of the passage 13 to the opposite side of the shank, which is usually of reduced size. Around the threaded portion 13 is a disc-like portion 16 adapted to bear against one end of the reservoir 1, and on the opposite side of the shank an annular enlargement 15 is provided. The latter has a transverse guide 17 extending therefrom over the centre of the shank and its passage 14; on the guide is a 80 shutter 18 movable at right angles to the direction of the passage 14 and adapted to close the latter. 18a is an extension on the shutter 18 intended for a finger hold so that the shutter may be more readily moved.

85 Around an annular wall 19 by which the portions 15 and 16 are connected and within the latter bristles 20 are so arranged as to project outwardly beyond the shank 12. These bristles are suitably cemented together at their inner ends and 21 designates a band of flexible material which encircles them and to which the outer bristles are preferably made to adhere. This band may consist of celluloid or other suitable material.

90 95 Figure 5 shows a simple method of filling the reservoir 1. A container 22 has its open end screwed into the threaded neck 4, and, after the container has been torn as at B

to admit air at its end remote from the reservoir, the plate 9 is turned so as to move the disc 6 away from the container 22. The contents of the latter is then transferred 5 into the reservoir by suction as movement of the disc 6 is continued.

Referring now to Figures 6, 7 and 8. Figure 6 shows the brush shank 12 mounted directly on a container or tube 22; in this 10 case the internally threaded portion 13 engages threads 22a on the neck of the tube. The annular wall 19 connects the disc-like portion 16 with the annular enlargement 15 of the shank 12; and a shutter 18 and its 15 extension 18a is slidable on a guide 17 and is adapted to close the passage 14. 25 is a pin projecting from the annular enlargement 15 to prevent complete disengagement of the shutter 18 from the slide 17 though other 20 means for accomplishing this purpose may be provided. In this construction the space for the inner ends of the bristles is somewhat differently formed, but in either case it is found that the bristles so largely surround the passage 14 that the contents of 25 the reservoir or tube is readily and completely picked up by them as it is passed through the passage 14.

While in the foregoing the preferred embodiment of the invention has been described and shown, it is understood that the constructions herein described are subject to such alterations and modifications as fall 30 within the scope of the appended claims.

335 What I claim as my invention and desire to secure by Letters Patent is:

1. A fountain brush consisting of a reservoir and a brush having a tubular shank, a threaded spindle arranged longitudinally in said reservoir, means for turning said spindle, a disc carried by said spindle so that as the latter is rotated the disc is moved longitudinally of said reservoir, a tubular neck on said reservoir adapted to receive either a tube from which the reservoir may be filled or the tubular shank of the brush through which the contents of the reservoir may be discharged.

2. A fountain brush consisting of a reservoir, a brush having a tubular shank, a threaded spindle arranged longitudinally in said reservoir, means for turning said spindle, a disc carried by said spindle so that as the latter is rotated the disc is moved longitudinally of said reservoir, a tubular neck on said reservoir, said tubular neck having both an external thread to receive the annular shank of the brush through which the contents of the reservoir may be discharged, and an internal thread to receive a tube from which the reservoir may be filled.

3. A fountain brush consisting of a shank having an axially projecting central portion, said shank and said central portion

having an opening formed axially therethrough, an annular portion extending from said shank which encircles said central portion and is spaced therefrom, a guide on the outer extremity of said central portion and extending to said annular portion so that a substantially U-shaped space is formed around said central portion and within said annular portion, a slide movable in said guide adapted to close the opening at the outer end of said central portion, bristles mounted in said U-shaped space between said guide and said annular portion and projecting outwardly beyond the latter, and a reservoir secured to the extremity of said shank remote from its projecting central portion so that soap in a substantially liquid state may pass from said reservoir into and through said opening.
